UNITED STATES PATENT OFFICE.

EMIL STREITZ, OF FREIENWALDE, PRUSSIA, GERMANY.

CENTRIFUGAL BOLTING-MACHINE.

SPECIFICATION forming part of Letters Patent No. 329,097, dated October 27, 1885.

Application filed May 22, 1885. Serial No. 166,370. (No model.) Patented in Belgium April 30, 1885, No. 63,709, and in England April 30, 1885, No. 5,345.

To all whom it may concern:

Be it known that I, EMIL STREITZ, of Freienwalde, in the Kingdom of Prussia and Empire of Germany, have invented certain new and useful Improvements in Centrifugal Bolting-Machines, of which the following is a specification.

The object of this invention is to furnish an improved vertical centrifugal bolting-machine in which the air-pressure is uniformly distributed within the machine, and thereby a very effective action of the same obtained.

The invention consists of a bolting-reel formed of a wire frame or cage, having a bolting-cloth placed loosely thereon, and radial beaters attached to a hollow cylindrical shaft having open ends, air-openings, and a horizontal partition or diaphragm. The bolting-reel is inclosed by a frame having interior screens and exterior doors, the spaces between said screens and doors communicating by top and bottom channels with the hollow shaft for keeping up the circulation of the air.

The invention consists, further, of certain details of construction and combinations of parts, as will more fully appear hereinafter, and finally be pointed out in the claims.

In the accompanying drawings, Figure 1 represents a vertical central section of my improved bolting-machine; Fig. 2, a horizontal section of the same on line *x x*; Fig. 1; Fig. 3, a detail side view of the wire frame or cage of the bolting-reel; and Fig. 4 a horizontal section of the bolting-reel, drawn on a larger scale.

Similar letters of reference indicate corresponding parts.

a in the drawings represents a vertical tubular shaft that is provided with spider-frames *c c'* at the ends, to the hubs of which are attached the end shafts, *b b'*, that turn in step and neck bearings of the frame of the bolting-machine. The tubular shaft *a* is provided with a number of holes or slots, *a'*, and is preferably made of two parts that are separated at the center by a horizontal diaphragm or partition-plate, *x*, to which the shaft-sections are riveted by suitable angle-irons, as shown in Fig. 1. The horizontal partition *x* serves to deflect the air that is drawn in through the spider-frames at the upper and lower ends

of the shaft *a* and force it through the holes of the shaft in a direction as nearly at right angles to the bolting-cloth as possible, so that the circulation of the air takes place in two separate currents, an upper and a lower one, as indicated by arrows in Fig. 1. The tubular shaft *a* is provided with radial beaters *f f'*, which are connected by horizontal top and bottom shelves or disks, *t t'*, for holding them rigidly in position. The upper shelf, *t*, serves also as a distributing-plate for the meal supplied through the conveying-tube *e*. The outer edges of the beaters *f* are arranged with projecting strips *o*, of suitable elastic material, that pass along the inner surface of the bolting-reel. The rotating beaters are inclosed by the bolting-reel, which consists of a wire frame or cage around which the bolting-cloth is loosely applied. The cage is formed of circular top and bottom frames, *r r'*, vertical stays *r' r'*, and vertical parallel wires *s*, supported by the frames *r r'*, as shown in Fig. 3. The bolting-reel, formed by the wire cage *s* and the bolting-cloth *g*, is again inclosed by a frame, *p*, the panels of which are provided with downwardly-inclined sheet-metal deflectors *n* and screens *d*. The panels of the frame *p* are supported by upright corner-posts, and are again inclosed by exterior detachable doors *p'* between which and the screens vertical channels *l* are formed, which communicate at their lower ends by communicating-tubes *v* with a square bottom chamber, *v'*, that surrounds the lower part of the revolving shaft *a*, and at the upper part with a chamber, *v''*, which chambers communicate with the open ends of the tubular center shaft, *a*. The flour that is passed through the bolting-cloth is conveyed off through the channel *h*, while the coarser particles separated from the meal are passed through the channel *i'*, to which they are moved by the scraper *m*, attached to the bottom shelf or disk, *t'*.

The bolting-machine is operated in the following manner: The meal passes through the inlet-pipe *e* to the upper distributing shelf or disk, *t*, and from the same into the spaces between the rotating beaters *f*, which throw the meal by the action of centrifugal force against the bolting-cloth and conduct the same in a

spiral line along the same until the finer particles are separated from the coarser ones and conducted off, respectively, through the channels *h* and *i*. The vertical beaters *f* act in the 5 nature of a suction-fan by drawing in the air through the spider-frames at the ends of the tubular center shaft and forcing it through the openings of the shaft-sections in two separate currents through the bolting-cloth. As 10 the ends of the tubular shaft communicate with the top and bottom chambers of the bolting-machine, and the latter with the vertical channels between the screens and exterior doors the beaters draw the air that has been 15 forced through the bolting-cloth, screens, and channels back into the shaft, so that a continuous circulation of air is obtained and undue pressure in any part of the machine prevented, so that a very regular and effective 20 screening takes place.

In bolting-machines heretofore in use the air is gradually compressed to such an extent that the air is emitted through every chink and untight part of the frame to the outside, 25 so as to carry screened particles of flour along and cause the so-called "dusting" of the machine. By my arrangement dusting is entirely prevented, as an even pressure and circulation of the air is kept up in the machine. 30 Another important point is, that the machine draws in but little fresh air through the supply-opening, so that consequently but little moisture is passed into the machine, and thereby the "sweating" of the same prevented. 35 The sheet-metal deflectors prevent the choking of the screens, as they distribute the flour more uniformly over the screens. The most important point of novelty, however, consists in the use of a bolting-reel with a loose bolting-cloth, which is passed around a cage of 40 wire rods, by which the contact of the beaters with the bolting-cloth is prevented. By the loose mounting of the bolting-cloth the latter is continually kept in motion by the air-current and thereby freed of the adhering flour 45 particles.

The bolting-cloth can be applied to the supporting-frame in any suitable manner, either in large sections, as shown in Fig. 2, or in 50 smaller panels, so as to be of polygonal shape.

In either case the cloth is glued to the top and bottom frames.

The interior of the machine is readily accessible by the removable doors, so that any part of the reel can be readily repaired with- 55 out difficulty.

Having thus described my invention, I claim as new and desire to secure by Letters Patent—

1. The combination of a perforated and tubular center shaft having radial beaters, a bolting-reel having a loose exterior bolting-cloth, and inclosing-frame having interior screens, exterior doors, and top and bottom chambers which communicate with the channels between the screens and doors and with the tubular center shaft, substantially as set forth. 60

2. The combination of a tubular and perforated center shaft having open ends and a 70 horizontal partition, radial beaters attached to the shaft, a bolting-reel formed of a wire cage and a loose exterior bolting cloth, an inclosing-frame having exterior doors and interior screens, inclined deflectors inside of the 75 screens, and top and bottom chambers that communicate with the vertical channels between the screens and doors and with the tubular center shaft, substantially as set forth.

3. In a centrifugal bolting-machine, the 80 combination of a center shaft having radial beaters with a bolting-reel formed of a wire cage and loose exterior bolting-cloth, substantially as set forth.

4. In a centrifugal bolting-machine, the combination of a tubular and perforated air-distributing shaft having open ends and a horizontal partition, radial beaters attached to said shaft, connecting shelves or disks, and a bolting-reel formed of a wire cage and a loose 90 exterior bolting-cloth, substantially as set forth.

In testimony that I claim the foregoing as my invention I have signed my name in presence of two subscribing witnesses.

EMIL STREITZ.
